[57] CLAIM

The ornamental design for a pen, as shown and described.

DESCRIPTION

FIG. 1 is a front elevational view of a pen showing my

new design with the cap member in a stored position and the writing tip exposed;

FIG. 2 is a right side elevational view, the left side being a mirror image thereof;

FIG. 3 is a rear elevational view;

FIG. 4 is a top plan view;

FIG. 5 is a bottom plan view;

FIG. 6 is a front elevational view with the cap member in a closed position;

FIG. 7 is a right side elevational view of FIG. 6, the left side being a mirror image thereof;

FIG. 8 is a rear elevational view of FIG. 6;

FIG. 9 is a bottom plan view of FIG. 6;

FIG. 10 is a front elevational view of a second embodiment of my new design with the cap member in a stored position and the writing tip exposed;

FIG. 11 is a rear elevational view of FIG. 10;

FIG. 12 is a right side elevational view of FIG. 10, the left side being a mirror image thereof;

FIG. 13 is a bottom plan view of FIG. 10;

FIG. 14 is a top plan view of FIG. 10;

FIG. 15 is a front elevational view of FIG. 10 with the cap member in a closed position;

FIG. 16 is a right side elevational view of FIG. 15, the left side being a mirror image thereof;

FIG. 17 is a rear elevational view of FIG. 15;

FIG. 18 is a bottom plan view of FIG. 15;

FIG. 19 is a front elevational view of a third embodiment of my new design with the writing tip extended;

FIG. 20 is a right side elevational view of FIG. 19, the left side being a mirror image thereof;

FIG. 21 is a rear elevational view of FIG. 19;

FIG. 22 is a top plan view of FIG. 19;

FIG. 23 is a bottom plan view of FIG. 19;

FIG. 24 is a front elevational view of FIG. 19 with the writing tip retracted;

FIG. 25 is a right side elevational view of FIG. 24, the left side being a mirror image thereof;

FIG. 26 is a rear elevational view of FIG. 24; and,

FIG. 27 is a bottom plan view of FIG. 24.

The top plan views of FIGS. 6, 15 and 24 are identical to FIGS. 4, 14 and 22, respectively.
